Primary Examiner — Cynthia Ramirez*Assistant Examiner* — Michael A Maharajh(74) *Attorney, Agent, or Firm* — Rabin & Berdo, P.C.(57) **CLAIM**

The ornamental design for a massager, as shown and described.

DESCRIPTION

FIG. 1 is a perspective view of a massager;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged perspective view of the portion designated in FIG. 1; and,

FIG. 9 is an enlarged portion of the massager as designated in FIG. 6.

The dash-dot broken lines shown are for the purpose of showing enlarged areas, and form no part of the claimed design.

The broken lines depict portions of the massager that form no part of the claimed design.

1 Claim, 7 Drawing Sheets(56)
